UNITED STATES PATENT OFFICE

109,160

DESIGN FOR A BIRD CAGE

Edgar Stern, New York, N. Y., assignor to Hartz Mountain Products, Inc., New York, N. Y., a corporation of New York

Application December 11, 1937, Serial No. 73,540

Term of patent 3½ years

To all whom it may concern:

Be it known that I, Edgar Stern, a citizen of the United States, resident of Manhattan, in the county of New York and State of New York, have invented a new, original, and ornamental Design for a Bird Cage, of which the following is a specification, reference being had to the accompanying drawing, forming part thereof.

Figure 1 is a perspective view of a bird cage showing my new design, and Figure 2 is a plan view thereof.

I claim:

The ornamental design for a bird cage substantially as shown.

EDGAR STERN.
